UNITED STATES PATENT OFFICE.

FERDINAND C. SCHWEDTMAN, OF ST. LOUIS, MISSOURI.

SASH-WEIGHT.

No. 883,979.

Specification of Letters Patent.

Patented April 7, 1908.

Application filed October 26, 1907. Serial No. 399,352.

To all whom it may concern:

Be it known that I, FERDINAND C. SCHWEDTMAN, a citizen of the United States, residing at St. Louis, Missouri, have invented a certain new and useful Improvement in Sash-Weights, of which the following is a full, clear, and exact description, such as will enable others skilled in the art to which it appertains to make and use the same, reference being had to the accompanying drawings, forming part of this specification, in which—

This invention relates to sash weights, and particularly to that type which consists of a metal shell or housing incasing a core formed by the material of which the weight is essentially composed.

The object of my present invention is to provide a sash weight of the type referred to in which one end of the metal shell or housing is closed by a member in which the edge portion of the shell is embedded, said member being preferably provided with a cord-securing means. I prefer to form said member from metal that is cast around the end portion of the incasing shell and also provide said member with an integral projection having an opening for receiving the cord which supports the sash weight, but, if desired, the cord-securing means can be formed by a separate piece that is secured to said member.

Figure 1 is a side elevation of a sash weight constructed in accordance with my invention; Fig. 2 is a detail top plan view of the upper end of the shell before the member which closes same has been connected thereto; Fig. 3 is a longitudinal sectional view of one form of mold which I can use in forming the member which closes the upper end of the shell; and Fig. 4 is a longitudinal sectional view of a slightly modified form of my invention.

Referring to the drawings which illustrate the preferred form of my invention, 1 designates a metal shell or housing that incases the core or material 2 of which the weight is essentially composed. I have herein shown the core as consisting of ground barytes but it is immaterial, so far as my broad idea is concerned, what kind of material is used for the core so long as it is material having proper specific gravity. The shell 1 is preferably of rectangular shape in cross section and is formed from sheet metal, the lower end portion of the shell being bent or folded inwardly to close the shell. Preferably, the

folded portions of the shell are embraced by a clip 3 through which fastening devices 4 extend. The upper end of the shell is closed by a member 5 formed from cast metal and provided with an integral projection 6 having an eye or opening 7 for receiving the cord which supports the weight. I prefer to connect the member 5 and shell 1 together by crimping or corrugating the upper end portion 1^a of the shell and bending it inwardly, as shown in Fig. 2, and then casting the member 5 around said crimped portion. This can be done by placing the crimped shell in a sectional mold A, as shown in Fig. 3, and sustaining it so that its crimped portion 1^a is located adjacent the bottom of the mold and then pouring in the molten metal which forms the member 5. The mold A is so shaped that a member 5 having an integral perforated projection 6 will be produced. The shell 1 is then filled with the material 2 which forms the core, preferably before the shell is removed from the mold, and thereafter the lower end portion of the shell is folded or bent inwardly and secured together as previously described. The member 5 not only forms a closure for the end of the shell but also adds to the weight of the article.

If desired, the core of the weight can be formed from granular material such, for example, as barytes, and metal which is poured over the granular material while in a molten state, Fig. 4 illustrating a sash weight constructed in this manner. The main advantage of forming the core of the weight from granular material and metal which is poured over same while in a molten state, is that I am enabled to produce articles of different weights with a uniform length of tube or incasing shell. For example, a tube or shell 13 inches long filled with barytes, as shown in Fig. 3, will weigh about 7½ pounds. By pouring molten metal over the barytes so as to fill the spaces between the particles of barytes I increase the weight of the article without increasing the dimensions of same. If it is desired to produce an 8½ pound weight I pour three pounds of molten iron over four pounds of barytes, and if it is desired to produce a 9½ pound weight I pour six pounds of molten metal over two pounds of barytes, the shell and its eye, weighing 1½ pounds in each case.

Another advantage of constructing the weight in this manner is that the core is

formed integral with the member that closes the end of the shell as the molten metal which is poured over the granular material percolates through said material and adheres 5 to the metal which forms the end closure for the shell. If desired, both ends of the shell can be embedded in cast metal which closes the ends of the shell and instead of forming the core of the weight from barytes and 10 molten metal, as shown in Fig. 4, the core can be formed entirely from metal which is poured into the shell while in a molten state.

Having thus described my invention, what I claim as new and desire to secure by Letters 15 Patent is:

1. A sash weight composed of a core, a shell incasing said core, and a cast member forming a closure for said shell and having the entire edge portion of the shell completely embedded therein; substantially as described.
2. A sash weight composed of a core, a shell incasing said core, a cast member forming a closure for the end of said shell and having the edge portion of the shell completely embedded therein, and means on said member to which a supporting cord can be attached; substantially as described.
3. A sash weight composed of a core, a metal shell incasing said core, and a metal cast member forming a closure for said shell and having portions of the edge of the shell completely embedded therein; substantially as described.
4. A sash weight composed of a core, a metal shell incasing said core, a metal cast member forming a closure for said shell and having portions of the edge of the shell completely embedded therein, and means on said member to which a supporting cord can be connected; substantially as described.
5. A sash weight composed of a core, a

metal shell incasing said core, and a metal member cast upon the end portion of said shell to form a closure for same and provided with an integral device to which a supporting cord can be attached, said metal member extending beyond the end of the shell; substantially as described. 45

6. A sash weight composed of a core, a metal shell incasing said core and having its end crimped, and a metal member arranged at the end of said shell and cast upon said crimped portion to form a closure for the shell; substantially as described. 50

7. A sash weight composed of a core, a metal shell incasing said core and having its end crimped, and a metal member cast upon said crimped portion to form a closure for the shell and provided with an integral projection to which a supporting cord can be attached; substantially as described. 55

8. A sash weight comprising a core, a shell incasing said core, and a metal member located beyond the end of the shell and cast upon said end to form a closure for same; substantially as described. 60

9. A sash weight comprising a core, a shell incasing said core, and a metal member cast upon portions of the end of said shell to form a closure for same; substantially as described. 65

10. A sash weight comprising a core, a metal shell incasing said core, and a metal member cast upon the end of said shell to form a closure for same and being connected to the core; substantially as described. 70

In testimony whereof I hereunto affix my signature in the presence of two witnesses, this twenty-second day of October 1907.

FERDINAND C. SCHWEDTMAN.
